[57] **CLAIM**

The ornamental design for a camera, substantially as shown and described.

DESCRIPTION

FIG. 1 is a front and top-right perspective view of a camera showing my new design;

FIG. 2 is a bottom plan view thereof;

FIG. 3 is a left-side elevational view thereof; and

FIG. 4 is a rear elevational view thereof.

The strap shown in FIG. 1 has been shown broken-away in FIGS. 2-4 for ease of illustration.

FIG. 3

FIG. 4
